(57) **CLAIM**

The ornamental design for a door handle for refrigerator, as shown and described.

DESCRIPTION

FIG. 1 is a front perspective view of a door handle for refrigerator according to an example embodiment of the design;

FIG. 2 is a rear perspective view thereof;

FIG. 3 is a front view thereof;

FIG. 4 is a rear view thereof;

FIG. 5 is a left side view thereof (a right side view thereof is a mirror image of this);

FIG. 6 is a cross-sectional view thereof taken about line I-I in FIG. 3;

FIG. 7 is a top view thereof (a bottom view thereof is a mirror image of this); and,

FIG. 8 is a cross-sectional view thereof taken about line II-II in FIG. 3.

The fine lines illustrated in figures are only for the three-dimensional effect of the product, and do not constitute the shape of the design.
